CLAIM

The ornamental design for a clamp for ATV, boat, and/or jetski, as shown and described.

DESCRIPTION

FIG. 1 is a front perspective view of a clamp for ATV, boat, and/or jetski with a speaker embodying my new design;

FIG. 2 is a front elevation view thereof;

FIG. 3 is a side elevation view thereof;

FIG. 4 is a bottom plan view thereof; and,

FIG. 5 is a top plan view thereof.

The broken lines showing of a speaker is included for the purpose of illustrating environmental context and forms no part of the claimed design.

The broken lines in the drawings that depict portions of the clamp for ATV, boat, and/or jetski that form no part of the claimed design.

1 Claim, 5 Drawing Sheets
